UNITED STATES PATENT OFFICE.

FRANK M. STEVENSON, OF SHARON, PENNSYLVANIA, ASSIGNOR TO THE PETROLEUM IRON WORKS COMPANY, OF SHARON, PENNSYLVANIA.

BAND-ANCHOR FOR TANK-CARS.

1,319,632.

Specification of Letters Patent.

Patented Oct. 21, 1919.

Application filed April 22, 1918. Serial No. 230,061.

To all whom it may concern:

Be it known that I, FRANK M. STEVENSON, a citizen of the United States, residing at Sharon, in the county of Mercer and State 5 of Pennsylvania, have invented certain new and useful Improvements in Band-Anchors for Tank-Cars, of which the following is a specification, reference being had therein to the accompanying drawing.

10 My invention consists of an improvement in band anchors, adapted to be used in connection with the terminals of holding bands of tank cars, or the like.

One of the particular objects in view is to 15 provide a band anchor of the type herein set forth, of simple, cheap and efficient construction, having means for effectively locking the band and its securing means in place.

A further object is to provide a band anchor of improved construction whereby the band may be easily and quickly manipulated, applied, secured and detached.

My improved band anchor comprises, generally stated, a base portion capable of 25 attachment to the under frame of a car having an extended clevis or bracket portion adapted to receive and hold the terminal of the band, and to coöperate with tightening and locking members adapted to hold the 30 band in position in the base portion of the bracket.

Preferred forms of the invention are shown in the accompanying drawings, in which:

35 Figure 1 is a transverse sectional view of a tank car and its underframe, provided with my invention.

Fig. 2 is an enlarged sectional view showing the device in edge elevation as applied 40 to one of the center sills.

Fig. 3 is a projected face view of the anchor, detached.

Fig. 4 is a similar view, showing the inner side.

45 Fig. 5 is a detail perspective view of the washer.

Fig. 6 is a similar view of the nut locking washer plate.

Fig. 7 is a view similar to Fig. 2 showing a modified construction.

Fig. 8 is an inner face view of the same.

Fig. 9 is a detail perspective view of the washer plate used with said construction.

55 Referring more particularly to Figs. 1 to 6 of the drawings, A designates a tank of

any usual construction, and B designates the longitudinal channel supporting or center sill members of a car.

An anchor band *a* of the usual construction, of which there are usually several, 60 passes over and around the tank A and has its free threaded ends secured in the anchors 2 secured to the center sills B.

My improved anchor comprises a back plate or base 3 having apertures 4 therein 65 for the reception of securing bolts or rivets 5 for attachment to one or the other center sill B and a bottom plate or bracket 6 extending downwardly and outwardly at an angle from the back plate 3. The bottom 70 plate 6 is slotted as at 7 forming side bearing cheeks 8, having terminal retaining lugs 9 formed on the under sides of the ends of the bearing cheeks 8. The top portion of the back base plate 3 extends outwardly by an 75 extension 10 engaging the upper flange of the center sill and centrally spaced walls 11 extend from the base plate 3 outwardly providing with ribs 11^a bracing members for the bearing cheeks 8. 80

A square edged washer 12 is adapted to be passed over the threaded end of the upset cylindrical end *a'* of band *a*, and one of its side edges is located to abut against the lugs 9 to prevent outward movement of 85 the band when tightened. A nut locking washer plate 13 of rectangular apertured form is adapted to be passed over the free end of the band *a* between the washer 12 and a holding nut 14. One end of the plate 13 90 is bent upwardly forming a flange 15 adapted to snugly engage against the inner side of the washer 12, and the other end of plate 13 is adapted to be bent downwardly 95 against the usual securing nut 14 by its securing flange portion 16.

In Figs. 7, 8 and 9, I have shown a somewhat modified form of anchor adapted to be made of pressed steel. In this construction I preferably make the back plate in 100 two right and left hand sections 3^a and 3^b having apertures 4^a for the reception of rivets or bolts. The inner portions of the sections 3^a and 3^b are bent outwardly to form downwardly extending bracing walls 105 11^b, and these members are secured together in spaced relation by a spacing thimble 17 and bolt 18. In this construction the bottom plate 6 is disposed of and the band *a* is secured by its terminal *a'* between the 110

bracing walls 11^b. The forward ends of the walls 11^b are bent outwardly in opposite directions to form retaining flanges 9^a, and a rectangular washer plate 12^a is adapted to be pressed over the free threaded end of the band terminal a' having its ends bent upwardly forming retaining lips or flanges 19 adapted to abut by their outer edges against flanges 9^a to prevent outward movement of the band, while the inner face of the washer engages directly against the edges 8^a of the walls 11^b.

It will be seen from the foregoing description that I have devised a novel and useful anchor, that will securely hold the band terminal and will be easily manipulated, allowing for insertion and removal of the threaded end of the band and its parts, and tightening or loosening, while positively preventing disengagement when adjusted to tightened position.

The slope or angle of the bearing cheeks 8 or of edges 8^a is arranged substantially at right angles to the center line of the band terminal a' so that the washer 12 or 12^a bears equally against their faces, thus evenly distributing the strain without tendency to slippage, and providing a solid bearing at all times.

The slotted arrangement facilitates the application or removal of the terminals of the band to the anchor at either side without entire removal of the nut and washer, so that the parts may be loosely assembled and tightened or loosened and quickly adjusted to operative position.

The invention may be changed in design or details or otherwise modified within the skill of the ordinary mechanic to suit different construction of cars, or conditions of use, but all such changes are to be considered as within the scope of the following claims.

What I claim is:

1. A tank band anchor comprising a body portion having a slot therein adapted to receive a band terminal between downwardly extending bearing portions on each side of said slot, and means coöperating with said terminal and said bearing portions to retain and prevent outward movement of said terminal.

2. A tank band anchor comprising a body portion having a slotted portion extending downwardly at an angle for the reception of the band terminal and its nut.

3. A tank band anchor comprising a securing base having a portion extending downwardly at an angle thereto and having

a slot therein for the reception of a band terminal, and securing means coöperating with said terminal and said downwardly extending portion for holding and preventing accidental displacement thereof.

4. A device of the class described comprising a base portion having a deflected abutment portion provided with a slot for the reception of a band terminal, lugs adjacent said slot, and means abutting said lugs and coöperating with said terminal for holding and preventing outward movement thereof.

5. A device of the class described comprising a body portion having an open ended slot therein for the reception of a band terminal, outwardly extending flanges on each side of said slot, and means coöperating with said band for preventing said band being disengaged from said slot.

6. In combination with a tank band and its terminal, an anchor comprising an attachable base portion having an open ended slot therein, said terminal being adapted to pass through said slot, and means for holding and preventing accidental displacement of the terminal.

7. In combination with a tank band and its terminal, an anchor comprising a body portion having an open ended slot therein for the reception of said terminal, lugs adjacent the open end of said slot, a member telescopically engaging said band and abutting against said lugs, and a holding nut.

8. In combination with a tank band and its terminal, an anchor comprising a body portion, a downwardly extending slotted portion adapted to receive said band, lugs adjacent the forward end of said slotted portion, an apertured plate on said band and abutting against said lugs, a nut on said band, and means coöperating with said apertured plate and said nut for locking said nut in place.

9. In combination with a car underframe member, a tank band anchor having a base secured to said member at each side of a central clearance slot and provided with a pair of downwardly and outwardly disposed bracing cheeks having inclined bearing portions and retaining lugs at each side of said slot, and adapted to receive and retain a washer when used in connection with the terminal of a tank band and its holding nut.

In testimony whereof I hereunto affix my signature in the presence of two witnesses.

FRANK M. STEVENSON.
